REVERSIBLE-CYCLE HEATING AND
COOLING SYSTEM

Charles Kerr, Jr., Edgewood, and John K. Stott,
Wilkinsburg, Pa., assignors to Westinghouse
Electric & Manufacturing Company, East
Pittsburgh, Pa., a corporation of Pennsylvania

Application March 1, 1933. Serial No. 659,197

7 Claims. (Cl. 62—6)

Our invention relates to heating and cooling systems utilizing the refrigeration cycle or the reversed refrigeration cycle for either cooling or heating as may be required. Our invention has 5 particular relation to such a system as adapted for use in connection with freight cars, many of which are required to start out from a warm place, such as Florida, with perishable goods requiring refrigeration to keep them from spoiling, 10 and to deliver the goods at a cold place, such as Maine, where heating may be required in order to prevent the goods from freezing.

Our invention relates to a system which is particularly adapted to meet the above-outlined condition, together with suitable control equipment therefor, although our invention, in its broader aspects is not limited to railway service.

With the foregoing and other objects in view, our invention consists in the systems, circuits and 20 apparatus hereinafter described and claimed, and illustrated in the accompanying drawing, the single figure in which is a very diagrammatic view of the essential equipment illustrating one form of embodiment of our invention.

25 We utilize a refrigerating unit which may be disposed underneath a freight car, or, in general, outside of the room to be heated or cooled. The refrigerating unit comprises, in its essentials, a compressor 1 which delivers a refrigerant fluid, in vapor form, to a condenser 2, in which the fluid is cooled sufficiently to condense it to a liquid, which is then delivered, through a small pipe 3, to an evaporator 4 in which the fluid is evaporated into vapor form, the vapor being returned, 30 at low pressure, through a return-pipe 5, to the compressor 1, where the cycle is continuously repeated.

It will be observed, in the foregoing refrigerating cycle, that the condenser gives out heat to 40 the ambient atmosphere, whereas the evaporator extracts heat from the ambient atmosphere, the refrigerating unit thus operating to transfer heat from one place to another at different temperatures. In accordance with our invention, we 45 place the condenser 2 in one compartment or chamber, designated by the numeral 6, and the evaporator 4 in another compartment or chamber, designated by the numeral 7, said chambers being disposed in side-by-side relation, by which 50 we mean that their intake ends are in substantially the same planes, and their outlet ends are in substantially the same planes. In other words, "side-by-side" is meant to include both lateral juxtaposition and vertical juxtaposition.

55 We also provide a system of shutters 8 and 9,

or their equivalent, whereby the condenser chamber 6 may be opened, at both ends, either to the outside air or to the air which is circulated through the refrigerator car, while, at the same time the evaporator chamber 7 is opened, at both 60 ends, either to the bar circulation system or to the outside air. When the shutters 8 are open, as shown in the drawing, the condenser chamber 6 is in communication with the outside air and is shut off from the air which is circulated through the car, while, at the same time, the evaporator chamber is in the path of the air which is circulated through the car. When the shutters 9 are open, the reverse process takes place, the inside air passing through the condenser and the outside air passing through the evaporator. It will 70 be readily understood that when the inside air passes over the evaporator, as shown, the car will be cooled, whereas, when the inside air passes over the condenser, the car will be heated.

In accordance with our invention, the foregoing results are accomplished very simply by placing the condenser and evaporator chambers 6 and 7 side by side so that their ends are in the same planes, respectively. We are thus enabled to utilize only one shutter rod 10 at each end of these chambers, and we can by this simple expedient operate all of the shutters 8 and 9 by pushing the shutter rods longitudinally. The adjustment of the positions of the shutter rods is effected by 80 means of solenoids or other electrical devices 11 and 12, the solenoids 11 being utilized to pull the rods into the shutter position shown in the drawing, whereas the solenoids 12 adjust the rods to the contrary shutter position.

It will be noted that the inner shutters 9 on the intake side of the condenser chamber are adjacent to the inner shutters 8 on the intake side of the evaporator chamber, and these two groups of shutters are in communication with what may 95 be termed a compressor chamber 13 which is in communication with a duct 14 through which air is extracted from the car which is to be heated or cooled in accordance with our invention.

On the outlet sides of the condenser and evaporator chambers 6 and 7, the inner shutters 9 of the former are likewise adjacent to the inner shutters 8 of the latter and these two groups of shutters are in communication with a duct 15 which returns the conditioned air to the car, 100 said air having been cooled as it has passed through the evaporator because of the open position of the shutters 8, as shown in the drawing, or having been heated by reason of passing through the condenser in the other position of 105 110

the shutters in which the shutters 9 are open and the shutters 8 are closed.

In the particular system illustrated in the drawing, the compressor 1 is coupled to two motors, namely a polyphase motor 16 and a direct-current machine 17 which may serve either as a motor or as a generator, the compressor and the motors being disposed in the compressor chamber 13 so as to be cooled by the circulated air.

10 The direct-current machine 17 is adapted to be connected to a direct-current battery-circuit 18 which is connected across the terminals of a storage battery 19 carried by the car. The battery is kept charged by any suitable means, the details of which are not essential to our present invention. The alternating-current motor is adapted to be energized from a detachable plug connection or other coupler 20 which may be connected to a wayside source of three-phase current, when 20 the car is standing at a station during loading or unloading or awaiting loading or unloading. The relative speeds of the alternating-current motor 16 and the direct-current machine 17 are such that when the plug connection 20 is energized from an external alternating-current source, the alternating-current motor will drive the direct-current machine as a generator so that it can be charging the battery 19.

It is possible to leave the compressor motors 30 running all of the time, either from the direct-current source or from the alternating-current source, regulating the temperature of the car by the opening and closing of the shutters 8 and 9. It is usually desirable, however, for reasons of economy, to alternately start and stop the refrigerating cycle under the exigencies of the temperature-requirements within the car. To this end, we have shown, very schematically, a thermostat 21 which is disposed somewhere within the car. 40 This thermostat may have two contacts, namely, a contact 22 which is made when the car is too hot and a contact 23 which is made when the car is too cold, both contacts being out of contact with the heat-responsive contact-member at a certain intermediate temperature.

When the contact 22 is energized, by reason of a too-high temperature in the car, the shutter solenoids 11 are energized, so as to move the shutters into the position shown in the drawing, 50 so that the shutters 8 will be open and the shutters 9 will be closed, thereby circulating the air from the car through the evaporator 4 to cool said air, while the condenser 2 is cooled by means of outside air passing through it. When the 55 other thermostatic contact 23 is energized, by reason of the attainment of a too-low temperature in the car, the other shutter solenoids 12 are energized, thereby moving the shutters to the opposite position in which the shutters 8 are closed and the shutters 9 are opened, thereby 60 heating the air from the car by passing the same through the condenser 2, while the evaporator extracts heat from the outside air which is passed through it by reason of the opening of the shutters 9.

At the same time that either one of the thermostat contacts 22 or 23 is energized, a circuit will be completed through the actuating coil of an electromagnetic contactor 24 which is thus 70 made to close a plurality of contacts which complete the connection of the direct-current motor 17 to the direct-current line 18 of the storage battery 19 and to connect the alternating-current motor 16 to the plug 20 ready for operation in 75 case a wayside source of polyphase current is

utilized while the car is standing still. The two thermostat contacts 22 and 23 thus constitute parallel partial-energizing circuits with respect to the motor-controlling contactor 24, which may be actuated through either one of these thermostat contacts, without any discrimination as to which contact is made, whereas the shutter-control means is operated discriminatively in such way that the correct shutter position is assured according as the thermostat contact 22 or 23 is energized.

At an intermediate position of the thermostat, neither of the thermostat contacts 22 or 23 will be energized, in which event the actuating coil of the contactor 24 is also deenergized, thereby stopping the motors 16 and 17. It will be understood that any suitable starting circuits or other control circuits may be utilized for the motors 16 and 17, such systems being well-known and forming no essential part of the novel features embodied in our present invention.

Any suitable means may be utilized for maintaining the air-circulation which has been above described and which is indicated on the drawing by the single-ended arrows. A convenient method for maintaining this air-circulation is indicated every diagrammatically in the drawing, as consisting of two fans or blowers 30 which are driven from the shaft of the compressor motors 16 and 17, one fan or blower being disposed in the condenser chamber 6 and the other being disposed in the evaporator chamber 7.

In normal service, the compressor will usually be intermittently started and stopped as the thermostat alternately makes and breaks contacts with one of its terminals 22 or 23. Thus, when the train is travelling in a warm climate, the thermostat will make and break contact with its terminal 22 and will never make contact with its terminal 23. When the train reaches a moderate climate, the thermostat will remain disconnected from both contacts. If the train reaches a very cold climate, the thermostat will make contact intermittently with its cold terminal 23, thereby starting and stopping the compressor again, by operating the circulating system with the shutters in a position opposite to that which is illustrated, so that the car is heated during the intermittent periods when the compressor is operating.

While we have described our invention with particular reference to a refrigerator car, in order to have something concrete in mind while explaining the invention, it will be obvious that our invention is not limited to this particular application which we desire to be understood as purely illustrative. We desire, therefore, that the appended claims shall be accorded the broadest construction consistent with their language and the prior art.

We claim as our invention:

1. A reversible-cycle refrigerating and heating system comprising the combination, with a room to be cooled or heated, of a refrigerating unit comprising a condenser and an evaporator disposed in side-by-side relation, means for providing separate chambers for said condenser and said evaporator, two sets of closure means in each end of each of said chambers, the two outer sets of closure means of the condenser chamber and the two inner sets of closure means of the evaporator chamber being open for refrigeration and closed for heating, and the remaining sets of closure means being closed for refrigeration and open for heating, means for si- 135

- multaneously shifting all sets of closure means according as heating or refrigeration is desired, an air duct from the room leading to the two inner sets of closure means at one end of the condenser and evaporator chambers, an air duct leading to the room from the two inner sets of closure means at the other end of the condenser and evaporator chambers, the remaining sets of closure means being exposed to the outside air, 5 and means for maintaining drafts of air flowing from end to end through both the condenser chamber and the evaporator chamber.
2. A reversible-cycle refrigerating and heating system comprising the combination, with a room 15 to be cooled or heated, of a refrigerating unit comprising a compressor, a motor driving means therefor, a condenser and an evaporator, the condenser and the evaporator being disposed in side-by-side relation, means for providing separate 20 chambers for said condenser and said evaporator, two sets of closure means in each end of each of said chambers, the two outer sets of closure means of the condenser chamber and the two inner sets of closure means of the evaporator 25 chamber being open for refrigeration and closed for heating, and the remaining sets of closure means being closed for refrigeration and open for heating, means for simultaneously shifting all sets of closure means according as heating or 30 refrigeration is desired, an air duct from the room leading to the two inner sets of closure means at one end of the condenser and evaporator chambers, an air duct leading to the room from the two inner sets of closure means at the other end 35 of the condenser and evaporator chambers, the remaining sets of closure means being exposed to the outside air, means for maintaining drafts of air blowing from end to end through both the condenser chamber and the evaporator chamber, 40 and means for providing a third chamber disposed in the path of the air to and from the room, the compressor and its motor driving means being disposed in said third chamber whereby they are cooled by one of said drafts through the condenser 45 and evaporator chambers.
3. A reversible-cycle refrigerating and heating system comprising the combination, with a room to be cooled or heated, of a refrigerating unit comprising a condenser and an evaporator disposed in side-by-side relation, means for providing separate chambers for said condenser and said evaporator, two sets of closure means in each end of each of said chambers, the two outer sets of closure means of the condenser chamber and the two inner sets of closure means of the evaporator chamber being open for refrigeration and closed for heating, and the remaining sets of closure means being closed for refrigeration and open for heating, means 50 for simultaneously shifting all sets of closure means according as heating or refrigeration is desired, an air duct from the room leading to the two inner sets of closure means at one end of the condenser and evaporator chambers, an air duct leading to the room from the two inner sets of closure means at the other end of the condenser and evaporator chambers, the remaining sets of closure means being exposed to the outside air, thermostatically responsive means for shifting all sets of closure means and for ensuring that the closure means are in opposite settings under predetermined maximum and minimum temperature conditions in the room and for energizing the compressor motor means at either one of said maximum temperatures and deenergizing said compressor motor means at intermediate temperatures, and means for maintaining drafts of air blowing from end to end through both the condenser chamber and the evaporator chamber at least during the periods of operation of the compressor.
4. A reversible-cycle refrigerating and heating system comprising the combination, with a room to be cooled or heated, and a thermostat in the room for responding to conditions therein, of a refrigerating unit for transferring heat from one place to another at different temperatures, electro-responsive means for changing the direction of utilization of said heat-transfer whereby it is made effective for either heating or cooling said room, electro-responsive means for starting up and shutting down the refrigerating unit, two

parallel partial-energizing circuits either one of which will complete an energizing circuit for said starting-up and shutting-down means, means for energizing said two parallel partial-energizing circuits in response to predetermined maximum and minimum temperature indications of said thermostat and for deenergizing said two parallel partial-energizing circuits at intermediate temperatures, and electro-responsive means for ensuring that said reverse-cycle means is in one condition as to direction of heat-transfer when one of said partial-energizing circuits is energized and in the other condition when the other of said partial-energizing circuits is energized.

15 7. A reversible-cycle refrigerating and heating system comprising the combination, with a room to be cooled or heated, of a refrigerating unit comprising a condenser and an evaporator disposed in side-by-side relation, means for providing separate chambers for said condenser and said evaporator, two sets of closure means in each end of each of said chambers, one set of closure means at each end of the condenser chamber and

one set of closure means at each end of the evaporator chamber being normally open for refrigeration and closed for heating, and the remaining sets of closure means being normally closed for refrigeration and open for heating, means for simultaneously shifting all sets of closure means according as heating or refrigeration is desired, partition means for providing two kinds of circulating air leading to and from said condenser and evaporator chamber, one kind of air being confined to the normally open sets of closure means in the two ends of one chamber and to the normally closed sets of closure means in the two ends of the other chamber, and the other kind of air being confined to the remaining sets of closure means, one kind of air including air circulated to and from the room, and the other kind of air being outside air, and means for maintaining drafts of air blowing from end to end through both the condenser chamber and the evaporator chamber.

CHARLES KERR, JR.
JOHN K. STOTZ.
